DESIGN FOR A BATHROOM SCALE

Carl W. Sundberg, Detroit, Mich.

Application March 24, 1944, Serial No. 113,035

Term of patent 14 years

(Cl. D52—10)

To all whom it may concern:

Be it known that I, Carl W. Sundberg, a citizen of the United States, residing at Detroit, in the county of Wayne, State of Michigan, have invented a new, original, and ornamental Design for a Bathroom Scale, of which the following is a specification, reference being had to the accompanying drawing, forming a part thereof.

In the accompanying drawing:

The figure is a perspective view of a bathroom scale showing my new design.

I claim:

The ornamental design for a bathroom scale, substantially as shown.

CARL W. SUNDBERG.
